REFRIGERATING SYSTEM

John Kirgan, Easton, Pa., assignor to Ingersoll-Rand Company, Jersey City, N. J., a corporation of New Jersey

Application July 26, 1934, Serial No. 736,994

12 Claims. (Cl. 62—152)

My invention relates to refrigerating systems in which a liquid refrigerant, such as water, is vaporized in part to give a cooling effect, and particularly to the regulation of systems of this kind.

An object of the invention is to provide a method and apparatus by which such a refrigerating system can be properly controlled so that it can be operated efficiently at less than full load.

In its preferred form the invention comprises an evaporator having multiple chambers in each of which the refrigerant is chilled by converting a portion thereof into vapor. The vapor is removed by suitable evacuator members such as steam jet boosters, and when it is necessary to reduce the refrigerating effect or output, one or more of the chambers in the evaporator are rendered inactive. For this purpose the admission of water to the chamber or chambers that are to be cut out and the supply of steam to the evacuators therefor are cut off. The invention comprises suitable means which is automatically actuated by the temperature of the cooled refrigerant for achieving this result.

The nature, objects and advantages of the invention are fully set forth in the ensuing description, and the novel features thereof are pointed out in the appended claims. But the disclosure is illustrative only and I may make changes which do not depart from the principle of the invention, or exceed the scope and spirit thereof.

On the drawing, Figure 1 is a view partly in section showing an outline of a portion of a refrigerating system according to my invention, and

Figure 2 is a cross section thereof illustrating the controlling connections for the evaporator and the connection of one of the evacuators to a condenser.

The same numerals identify the same parts throughout.

In practice I employ vessel 1, which is called an evaporator, to which a liquid refrigerant, such as water, is supplied by means of a conduit 2. After being chilled therein the water is discharged from the evaporator through a conduit 3 which conveys it to the place where the refrigerating effect is to be produced. When the water is again warmed it is returned through the pipe 2 to the evaporator to be chilled and used again. The evaporator has partitions 4 which divide the interior into several chambers and the pipe 2 is provided with branches 5 for each chamber. These pipes terminate inside the

chambers in headers 6 which are perforated to permit the water to issue in the form of several sprays. Within the chambers the pressure is reduced to such a point that some of the spray water is vaporized, extracting heat from the main body of the water and thus lowering its temperature to the required extent. Each of the chambers is connected to the discharge conduit 3 by a branch pipe 7, and has an outlet 8 leading to these branch pipes. The water vapor is removed from each chamber by means of steam jets 9, and the water which is converted into vapor is made up by replenishing the water in the system in any suitable way so as to maintain a full supply coming back through the conduit 2.

The evacuators for removing the vapor have the form of steam jet boosters or thermo-compressors. They include the nozzles 9 connected to a common steam supply pipe 10 by branches 11. These nozzles discharge into conduits 12 which are connected to a condenser 13. Each of the thermo-compressors has a lateral projection 14 secured to the outside of the evaporator and communicating through an opening 15 with one of the chambers therein. When the steam supply is on, the steam issuing from the nozzle 9 acts by aspiration to draw the water vapor out of the chamber. Of course, there is a separate evacuator means for each of the chambers in the evaporator 1.

When the system is operating at full capacity all chambers are, of course, used, but when the output is lessened one or more of the chambers is put out of action. The chamber at the extreme left in Figure 1 is illustrated as having a valve 16 in the line of the branch pipe 5. This valve is normally open, but is adapted to be closed to cut off the water for said chamber from the pipe 2. In the branch pipe 11 supplying steam to the evacuator for the same chamber is a similar valve 17. These valves are actuated by a fluid medium supplied by way of a pipe 18 having branches 19 to enable the fluid medium to actuate the valves 16 and 17. The operation of the valves 16 and 17 is accomplished by means of housings 20 and pressure diaphragms 21 therein. The valves 16 and 17 have arms 22 connected to rods 23 which enter these housings 20 and have heads 24 which engage the diaphragms 21. These rods are surrounded in the housings 20 by springs 25 engaging the heads 24 at one end and the inside of the housings at the other. Hence, the fluid in the conduit 18 acting upon the diaphragms 21 is opposed by these springs 25. The medium in the conduit 18 is necessarily under

pressure, and may come from any convenient source.

In the line of the conduit 18 is a valve 26 through which fluid must pass to the valves 16 5 and 17. The casing of the valve 26 has a drain pipe 27. This valve also has an arm 22 connected by a rod 28 to an expansible casing 29. The end of this casing to which the rod 28 is attached is movable, the other end of this casing being 10 held stationary. This casing is connected by a tube 30 to a bulb 31 in the delivery conduit 3, and the casing, the tube and bulb are filled with an expansible liquid. Therefore, when the temperature of the chilled water drops to a certain 15 point, the shrinkage of the liquid causes this casing to open the valve 26 and permit the fluid in the conduit 18 to actuate the diaphragms 21 and turn the valves 16 and 17 to closed position.

Adjacent the evaporator is a float container 20 32 connected to the delivery conduit 3 by a pipe 33. Within the container is a float 34 mounted on a lever which is pivoted within the container, and the journal or pivot, which is rigid 25 with this lever, may extend to the outside of the float container 32 and have fixed on its external end an arm 35. This arm is connected to a rotary valve member 36 in the pipe 2, this valve having an outside arm 22, and the arms 22 and 35 being coupled by a link 37. By means of this float the flow of water through the pipe 2 into the chambers of the evaporator, 1 can be so regulated that the level of the chilled water in the active evaporator chambers is maintained substantially constant.

To get this result, the pressure in the float chamber 32 is maintained the same as the pressure in the evaporator, and the float container therefor is connected by way of the pipe 38 and branches 39 to the inside of the chambers of 40 the evaporator. One of the pipes 39 contains a valve 41 similar to the valves 16 and 17, and connected to a similar diaphragm housing 20 and which is likewise provided with a connection 45 19 to the pipe 18. Hence, whenever one of the evaporator chambers is put out of action, the valve 41 of that chamber cuts off communication between said chamber and the pipe 38. Otherwise the pressure in the condenser, when the steam is cut off at the evaporator, would take 50 effect in the said chamber, and, since the condenser pressure is greater than normal evaporator pressure, the level of the water in the container 32 would be forced down and the function of the float 34 would be deranged. The discharge conduit 3 may have a pump 42 in the line 55 thereof to facilitate delivery of the chilled water to the place of use.

In action when the system is working at full load the valve 26 is in such position that the pipe 18 beyond it is connected to the drain pipe 27, and the pressure medium in pipe 18 is cut off from the valves 16 and 17 and 41. When the load drops, however, and the returning water is cooler, the chilled water will likewise be cooler 60 so that the casing 29 contracts to open the valve 26. Pressure fluid in the pipe 18 therefore actuates all of the diaphragms to close the valves 16, 17 and 41. These valves may close all at once or their springs may be so selected that they will close one after the other in any order required. Then the supply of steam and water to one chamber is cut off and so is communication of the chamber with the float container 32. The condenser pressure then forces down the level of 65 the water at the bottom of that chamber in the

evaporator to a point in the connection 1 above the conduit 3. The evaporator chamber cut out thus remains sealed by the water in the pipe 7 and the operation continues in the other chambers. 5

Of course, another pipe or conduit 18 and a second casing like the casing 29 and similar valves could be employed to cut out of action another one of the evaporator chambers as the load drops still further; or one casing 29 might 10 be used and the valve 26 might be so constructed that it would actuate the valves for one of the evaporator chambers to cut out this chamber and another chamber later in case the load drops still further. When the load becomes full again 15 the casing 29 expands and opens the valve 26 connected to the pipe 18 to the drain 27. Then the controlling means 16 and 17 and 41 are re-opened and the evaporator chamber which was not operating is again put into service. The 20 pipes 38 communicate with the chambers of the evaporator through ports 40.

The chambers of the evaporator may also be provided with valves or controlling means 43 25 in the inlet members 5, and similar means 44 in the pipes 11 wherever needed, so that the incoming steam and water for any one or all the chambers may be shut off by hand. With these valves, when the chamber equipped with the automatic valves is put out of use, another 30 chamber can be cut out to operate at still lighter load if desired, or all the chambers may be put out of service to stop the system.

Another purpose served by this invention is to prevent flooding of the evaporator in case the 35 water returns from a higher level through the pipe or inlet member 2. In such a case, whenever the system is shut down or if the pump should fail, the pressure in the evaporator chambers and the container 32 would still be equal, 40 and when the level of the liquid in the evaporator rises high enough the valve or controlling means 36 will be closed entirely. Hence no more water could flow into the evaporator. 45

I claim:

1. In a refrigerating system an evaporator having a chamber to which a liquid refrigerant is supplied to be cooled, means for regulating the refrigerant supplied comprising a float container having connection with said chamber, an evacuator for said chamber to remove vapor of the refrigerant therefrom, and means for interrupting communication between said container and said chamber, and rendering the evacuator inoperative under predetermined working conditions. 55

2. In a refrigerating system an evaporator having a chamber to which a liquid refrigerant is supplied to be cooled, a float container connected to said chamber, to control the admission of refrigerant thereto, and means acting responsively 60 to the temperature of the chilled refrigerant for automatically interrupting the admission of said refrigerant to said chamber and cutting off communication between said container and said chamber under predetermined working conditions. 65

3. In a refrigerating system comprising an evaporator having a chamber in which a refrigerant is chilled, a float container connected to said chamber to control refrigerant entering the latter, and means acting responsively to the temperature of the chilled refrigerant for cutting off communication between said container and said chamber under predetermined working conditions. 75

4. In a refrigerating system comprising an evaporator having separate chambers, a container having a float therein and being connected to the evaporator, an evacuator for each chamber, and automatic means for rendering the evacuator of one chamber inoperative and interrupting communication between said chamber and said container when the load drops.

5. In a refrigerating system comprising an evaporator having several chambers, means for admitting a liquid refrigerant to said chambers, a container having a float therein to control the admission of refrigerant to said chambers, and automatic means for stopping the admission of refrigerant to one of said chambers and cutting off the container from said chamber when the load drops.

6. In a refrigerating system comprising an evaporator having several chambers to receive a liquid refrigerant, a container having a float therein and being connected to each of said chambers, and automatic means for cutting off communication between the float container and one of said chambers when the load decreases.

7. In a refrigerating system comprising an evaporator having a chamber, means for admitting a liquid refrigerant to said chamber, a container having a float therein to control the level of the liquid in the chamber, said container being connected to said chamber, means for evacuating said chamber, and automatic means to interrupt communication of the float container with said chamber, to cut off the supply of refrigerant thereto and to render the evacuating means inoperative when the load decreases.

8. A refrigerating system comprising an evaporator having a plurality of chambers, means for admitting a liquid refrigerant to each of said chambers, a container having a float therein to control the level of the liquid in said chambers, said container being connected to each of said chambers, means for evacuating said chambers, and automatic means to interrupt the communication of the float container with one of said chambers, to cut off the supply of refrigerant to said chamber and to render inoperative the evacuating means therefor when the load drops.

9. In a refrigerating system the combination of an evaporator having a chamber, a pipe to supply liquid refrigerant to said chamber, a discharge pipe for said chamber, a container having a float,

said container being connected to the discharge pipe, a controlling member in the supply pipe connected to the float, a pipe connecting the container to the evaporator, a valve in said pipe, a housing, a diaphragm in the housing arranged to 5 actuate said valve, and means controlled by the temperature of the refrigerant to cause the diaphragm to close the valve and interrupt communication of the container with said chamber when the load drops.

10. A refrigerating system comprising an evaporator having multiple chambers for cooling a liquid refrigerant therein, a container having connection with each of said chambers, a float in the container, a discharge conduit also connected to 15 said chambers and said container, a supply pipe having a controlling member therein for said chambers, said member being connected to said float, a valve for controlling the communication of said supply pipe with one of said chambers, an 20 evacuator for said last-named chamber, a valve for said evacuator, a valve to control the connection of said container to said chamber, housings associated with said valves, diaphragms in the housings arranged to operate said valves, and 25 means controlled by the temperature of the refrigerant for enabling the diaphragms to be operated to close said valves.

11. The method of producing and controlling refrigeration which consists in cooling a refrigerant in a plurality of separate and equal masses, joining the cooled masses, automatically eliminating one or more of said masses in response to a drop in the temperature of the cooled refrigerant, continuing the cooling of the refrigerant in 35 the remaining masses and maintaining an equality between such remaining masses.

12. The method of producing and controlling refrigeration which consists in cooling a refrigerant in a plurality of separate and equal masses, 40 joining the cooled masses, maintaining the amount of refrigerant undergoing cooling in each of said masses substantially constant, automatically eliminating one or more of said masses in response to a drop in the temperature of the 45 cooled refrigerant continuing the cooling of the refrigerant in the remaining masses and maintaining an equality between such remaining masses.

JOHN KIRGAN. 50
